UNITED STATES PATENT OFFICE.

PATRICK KEEGAN, OF FALL RIVER, MASSACHUSETTS, ASSIGNOR TO DRAPER CORPORATION, OF HOPEDALE, MASSACHUSETTS, A CORPORATION OF MAINE.

TRANSFERRING MECHANISM FOR FILLING REPLENISHING LOOMS.

Application filed November 13, 1925. Serial No. 68,793.

This invention relates to transferring mechanism for filling replenishing looms and is more particularly directed to the means for holding the tip end portion of 5 the bobbin or filling carrier as it is transferred from the hopper to the shuttle.

When a filling carrier or bobbin is to be ejected from the shuttle and a new one substituted, the incoming filling carrier or bobbin is utilized to exert an expelling force 10 upon the outgoing filling carrier or bobbin, with the result that at times the incoming filling carrier or bobbin may be displaced in the shuttle—the tip portion may be either 15 too high or too low—with consequent injurious effects during subsequent weaving.

It has heretofore been proposed to provide means for acting upon the tip end of a bobbin as well as its head, in order to 20 overcome the difficulties above noted, and the present invention is directed to a simple and effective means for engaging and holding the tip of a bobbin to prevent misplacement of the bobbin during transfer to the 25 shuttle.

In accordance with the present invention, the usual transerrer is provided with a bobbin tip head on which are pivotally mounted at each side of its center bobbin 30 tip engaging jaws having tail portions, between which is movable a jaw operating member which will cause the jaws to engage the tip of a bobbin as the transerrer operates to transfer a filling carrier from the hopper to the shuttle, and then release 35 the tip of the bobbin as the transerrer starts back to its upper or inoperative position.

The invention and new combination of 40 parts will best be made clear from the following description and the accompanying drawings of one good form thereof.

In the drawings:

Fig. 1 is an enlarged end elevation at 45 the filling replenishing side of the loom, some of the parts being shown in section and others omitted for clearness of illustration;

Fig. 2 is an enlarged perspective detail 50 of the transerrer and bobbin tip engaging jaws of the present invention;

Fig. 3 is an end elevation of the bobbin tip engaging jaws as the parts appear during transferring operation; and

Fig. 4 is a perspective detail showing 55 more particularly the bobbin tip head with the cover plate removed.

It is now the common practice in filling replenishing looms to provide the shuttle with a new supply of filling when the filling 60 previously in use has become nearly exhausted, and in such cases a hopper or battery is usually provided for supplying the fresh filling carriers to the transferring mechanism.

In the present instance of the invention the hopper or battery is shown of the conventional type now in common use, and consisting of a rotary bobbin holder 1 having 65 portions 2 along its periphery for the support of the bobbins or filling carriers 3, and the rotary head 1 is herein shown as provided with a ratchet wheel 4 and means acting thereupon to rotate the hopper at intervals to bring a fresh filling carrier into 70 position for transfer, but since these details are not essential to the present invention and are now well-known in the art, further description thereof appears unnecessary.

The lay 5 may be of usual construction 80 and provided with the usual shuttle box having an open bottom 6 through which a filling carrier may be ejected during transfer, and the shuttle 7 in which the filling carrier is mounted may likewise be provided with the usual bottom opening for the passage of the filling carrier or bobbin. These parts are of usual construction.

The transerrer 8 is pivotally supported 85 upon the stud or dead shaft 9 and has the downwardly extending arm 10 to which is pivotally connected the dog 11, and the dog 11 is under the control of a train of mechanism for moving the dog into the path of the bunter 12 mounted on the lay when filling replenishment is to be effected. Since 90 such train of mechanism forms no part of the present invention and is now well understood by those familiar with the art, it is 95 not herein shown and described.

Mounted upon the end of the stud or dead shaft 9 is the fixed arm 13, now commonly employed in looms of this type, and pivotally mounted on the arm 13 at 14 is the tip support 15 which normally underlies the tip portion of the bobbin when in transferring position, as indicated in Fig. 1. So far as the present invention is con-

cerned, the tip support 15 may or may not be employed.

Secured to and extending laterally from the head 16 of the transerrer 8 is the rod 17 which in the present instance is shown as secured to the transerrer by means of a set screw 18. The rod 17 extends in substantial parallelism with the axes of the bobbins or filling carriers in the hopper, and at its outer end is provided with means for gripping and holding the end of the filling carrier during transfer. The supporting element for the parts to be hereinafter described may be conveniently designated as the bobbin tip head, and comprises the hub portion 19 to which is secured the plate 20, and these parts may be connected to the rod 17 by a proper securing device, such as the set screw 21.

20 Pivottally mounted on the bobbin tip head, one at each side of the center of such head, are the bobbin engaging jaws 22 and 23. The pivotal connection of the two jaws to the head may be variously contrived, but is herein shown as formed of the pins 24, one for each jaw, located at opposite sides of the substantially vertical longitudinal center of the bobbin tip head, as indicated in Figs. 3 and 4.

30 Each of the bobbin holding jaws 22 and 23 is thus pivottally mounted upon the head and is provided with a bobbin engaging portion 25 below the pivotal mountings, and with tail portions 26 extending upwardly from the pivotal supports 23 and 24.

40 Mounted on the head for movement relative to the jaws and to effect their opening and closing movements is a jaw closer 27, the upper stem portion of which is mounted for sliding movement in a guideway formed by a lug 28 secured to the head.

45 The jaw closer, more specifically described herein, has a wedge portion 29, which cooperates with complementary inclined surfaces 30 on the tail portions 26 of the jaws, the construction being such that movement of the jaw closer upwardly will cause the wedge 29 to act upon the tail portions of the jaws and close the jaw engaging portions 25 of 50 the jaws about the bobbin tip located between the jaws, and conversely, movement of the jaw closer in the opposite direction is utilized in effecting an opening movement of the jaw engaging portion of the jaws.

55 The jaw closer has a stem 31 extending downwardly between the jaws from the wedge portion 29 of the jaw closer, and between the upper end of the stem and the guiding recess formed in the block 28 is a 60 spring 32 normally acting lightly upon the jaw closer to move it downwardly into the position indicated in Fig. 4, which is the jaw open position.

65 The tail portions 26 of the jaws are normally under the influence of spring means

tending to move the tail portions towards each other, and perforce cause the bobbin engaging portion of the jaws to open. In the present instance of the invention the head 20 has extending therefrom a pin 33 about which is wound the coils 34 of a spring, the two arms 35 of which rest upon the tail portions 26 of the jaws above their pivotal supports, as indicated in Figs. 3 and 4, the result being that the action of the spring upon the tail portion of the jaws is to open the jaws when the jaw closer is moved downwardly by its spring 32.

Inasmuch as the features constituting the present invention are subject to the accumulation of lint during weaving, which may obstruct their free action, the present invention further contemplates a cover plate 36 which may extend over the head 20, as indicated in Figs. 2 and 3, and may enclose the movable parts included by the present invention. The cover plate 36 is provided with side flange portions 37 which overlie the edge portions of the head 20, and the cover plate is conveniently secured to the head by the screws 38, as indicated in Fig. 4, and the lower portion of the cover plate may be further secured to the head by means of the threaded end portions of the pivotal studs 24 on which the jaws are mounted. In this latter case, the ends of the pivots 24 would be passed through holes 39 of the cover plate and their outer ends be provided with suitable nuts 40.

When a bobbin is to be transferred to the shuttle, the transerrer is moved downwardly and the head 16 of the transerrer engages the head of the bobbin, while the tip end portion of the bobbin is first enclosed by the open jaw portions 25 of the jaws and then the extension 31 of the jaw closer contacts with the bobbin tip and is moved upwardly, thereby causing the wedge 29 of the jaw closer to positively close the jaws about the tip of the bobbin. When the bobbin has been placed in the shuttle by the transerrer and the transerrer starts upwardly to its inoperative position, the spring 32 acting upon the jaw closer moves the jaw closer downwardly, thereby permitting the spring arms 35 to move the tail portions of the jaw towards each other and the wedge 29 of the jaw closer descends, so that as soon as pressure is taken off the jaw closer, the jaw is opened by virtue of the spring 32 acting to return the jaw closer to its jaw open position.

What is claimed is:

1. In a filling replenishing loom, the combination of a hopper for filling carriers, a transerrer having an arm extending therefrom in substantially parallel relation to the bobbin to be transferred, a head fixed to said arm and having pivoted jaws to engage the tip of a bobbin to be transferred actuated by downward movement of the transerrer, a

jaw closing slide having upwardly converging inclines to separate the upper end of the jaws and close both jaws about the tip of a bobbin, and a spring for returning the jaw closing slide into normal position to permit both jaws to release the bobbin as the trans-
ferrer starts upwardly.

2. In a filling replenishing loom, the combination of a transferrer having spring separated pivoted jaws both of which are pivotally mounted to engage and hold the tip of a filling carrier during transfer, tail portions extending upwardly from the pivots of the jaws, a jaw closer having a wedge portion mounted for sliding movement between the tails of the jaws, and a spring normally tending to depress the jaw closer wedge to permit the spring separated jaws to open for the reception of the tip of the filling carrier but yieldable on transfer movement of the trans-
ferrer by engagement with the filling carrier to permit the two jaws to be positively closed by movement of the jaw closer wedge.

3. In a filling replenishing loom, the combination of a transferrer having two pivoted jaws to engage and hold the tip of a filling carrier, a head on which the jaws are pivoted at opposite sides of the vertical center line of the head, a spring acting upon the two pivoted jaws above their pivots to separate the jaws, a jaw closer mounted on the head for sliding movement between the two pivoted jaws and having a double incline or wedge converging upwardly to cause closing movement of the jaws as the jaw closer meets the tip of a filling carrier during the operation of the trans-
ferrer, and a spring for moving the jaw closer downwardly to permit the jaw opening spring to open both jaws as the trans-
ferrer starts upwardly to inoperative position.

4. In a filling replenishing loom, the combination of a trans-
ferrer having a bobbin tip head, two jaws both of which are pivotally mounted on the head at opposite sides thereof and having bobbin tip engaging portions below the pivots and tail portions extending upwardly from the pivots, a spring mounted on the tip head and engaging the tail portion of the jaws to separate the bobbin engaging portions of the jaws, a jaw closing slide mounted on the head and having a wedge portion between the tail portions of the jaws for closing both jaws upon the tip of a bobbin during transfer, and means for returning the jaw closing slide to initial position on upward movement of the trans-
ferrer.

5. In a filling replenishing loom, the combination of a trans-
ferrer having a bobbin tip head, two jaws pivotally mounted on the head and having bobbin tip engaging portions below the pivots and tail portions ex-

tending upwardly from the pivots, a spring mounted on the tip head and engaging the tail portion of the jaws to separate the bobbin engaging portions of the jaws, a jaw closing slide mounted on the head and having a wedge portion between the tail portions of the jaws for closing the jaws upon the tip of a bobbin during transfer, means for returning the jaw closing slide to initial position on upward movement of the trans-
ferrer, and a cover plate for the parts carried by the tip head to exclude lint and foreign matter.

6. In a filling replenishing loom, the combination of a trans-
ferrer having a bobbin tip head, two jaws pivotally mounted on the head, one at each side of the vertical central line of the head and having upwardly extending tail portions, a jaw closer extending between the pivots of the jaws and having a wedge to act upon the tail portions of the jaws, a spring normally acting to press the tail portions of the jaws into contact with the jaw closer wedge, and a spring normally acting to maintain the jaw closer wedge in jaw opened position.

7. In a filling replenishing loom, the combination of a trans-
ferrer having a bobbin tip head, a jaw pivotally mounted on the head at each side of its center and having tail portions provided with upwardly converging inclined surfaces, a jaw closer mounted for sliding movement on the head and having a wedge with upwardly converging inclined surfaces between the tail portions of the jaws, a spring normally holding the inclined surfaces of the tail portions and wedge in contact, and a spring for moving the jaw close in a downward direction to cause the two jaws to separate on upward movement of the trans-
ferrer and to release the bobbin tip.

8. In a filling replenishing loom, the combination of a trans-
ferrer having a bobbin tip head, a jaw pivotally mounted on the head at each side of its center and having tail portions provided with oppositely inclined surfaces, a jaw closer mounted for sliding movement on the head and having a wedge fixed thereto between the tail portions of the jaws, a stem on the jaw closer extending upwardly from the wedge, a fixed lug on the head having a guiding groove into which the stem extends, a spring normally holding the inclined surfaces of the tail portions and wedge in contact, a spring for moving the jaw close in one direction, and a cover for covering the parts carried by the head.

In testimony whereof, I have signed my name to this specification.

PATRICK KEEGAN.
